PULVERIZER MILL

Ernest E. Lynch, Alameda, Calif., assignor to
Thomas P. Bacon, Sr., Oakland, Calif.

Application June 24, 1941, Serial No. 399,478

3 Claims. (Cl. 83—45)

This invention relates to a pulverizer or ball mill.

An object of this invention is to provide a pulverizer of the ball mill type in which the pulverizing unit can be lifted out of the machine and replaced without requiring the disassembling or removal of any part of said unit or any other part of the machine.

Another object of this invention is to provide a pulverizer or ball mill in which the balls are driven in a bowl which also rotates in such a manner that the resultant grinding force urges the ground material outwardly and over the periphery of the bowl, and in which central feeding of the material is facilitated.

Another object of this invention is to provide a ball mill in which the balls are held between a bowl and a driving race and in which means of connection is provided between the bowl and the driving race to convert the rotation of one into rotary movement of the other but in opposite direction.

Another object of this invention is to provide a ball mill in which the balls are held between removable and replaceable grinding plates positively rotated in opposite directions to each other so as to rotate the balls in such a manner that the entire applied horse power is utilized in the reduction of ore, by reducing frictional resistance and providing opposite differential leverages or turning moments to the balls, and thereby increasing the ball speed without the necessity of an increase in centrifugal force in the bowl of the ball mill.

Another object of this invention is to provide a pulverizer or ball mill which is highly useful and simple in construction. Convenience of arrangement, lightness and comparative inexpensive manufacture are further objects which have been borne in mind in the production and development of the invention.

With the foregoing and other objects in view, my invention resides in the combination and arrangement of parts and in the details of construction hereinafter described and claimed, it being understood that changes in the precise embodiment of the invention hereinafter disclosed may be made within the scope of the appended claims without departing from the spirit of the invention.

The invention is clearly illustrated in the accompanying drawings, wherein:

Fig. 1 is a cross-sectional view of the ball mill.

Fig. 2 is a plan view of the driving head of the ball mill.

Fig. 3 is a plan view of the driving race of the ball mill.

Fig. 4 is a side view of the race of the ball mill.

Fig. 5 is a removable top race lining.

Fig. 6 is a sectional plan view showing the differential transmission in the column of the milling unit, and

Fig. 7 is a sectional fragmental view of the connection between the elements of the milling unit and the driving unit of my machine.

In carrying out my invention I make use of a milling or pulverizing unit 11 removably journaled in a transmission and support unit 12 in such a manner that a pulverizer unit can be connected at its top to a suitable lifting mechanism and be lifted out vertically from the bearing support unit 12.

In detail the bearing support unit 12 includes a base 13 suitably secured or held on a foundation or on the ground. A substantially cylindrical housing 14 is mounted on the base 13. The top 16 of the housing is dished from the center outwardly and downwardly and slopes toward a discharge lip 17 at one side thereof. A cylindrical shield 18 is held on top of the housing 14 so as to inclose a milling or grinding space above the dished top 16.

Inside of the housing 14 is a central hub 19 which is held on the bottom of the housing 14 by a suitably secured flange 21. The hub 19 is cylindrical. On the hub 19 rests a hub sleeve 22 so that the hub-sleeve 22 is journaled on and rotatable around the hub 19 as an axis. On the upper portion of the hub sleeve 22 is suitably fixed a beveled gear 23 which is in mesh with a gear 24 which latter in turn is driven by a drive shaft 26 extending from the outside into the housing 14 and suitably journaled in a bearing 27.

From the center of the dished housing top 16 and in axial alignment with the hub 19 extends a standard 28. The standard has a circular journal hole 29 therethrough which terminates at the top in a circular counter bore 31. On the shoulder 32, at the bottom of the counter bore is an antifriction trust bearing 33 for supporting the weight of the milling unit 11 thereon. The milling unit 11 has a shouldered stem 34 which fits into said counter bore 31 and hole 29 of the standard 28 so as to rotatably journal the pulverizing unit 11 in said standard. The shoulder 36 of this stem 34 rests on the trust bearing 33.

The pulverizing unit 11 has at the bottom of its stem 34 a squared end 37 which slidably fits

into a squared bore 38 in the top of the hub sleeve 22 of the driving mechanism in the housing 14. This establishes a separable driving connection between the milling unit 11 and the driving mechanism inside the supporting unit 12, which connection can be severed simply by lifting the milling unit 11 and its stem 34 out of the standard 28 and out of the hub sleeve 22.

The milling or pulverizing unit 11 has a bowl 41 mounted on the top of the stem 34. Inside of the bowl 41 is a lining or race 42 which is removably held in place by means of locking grooves 43 around its central aperture 44 which interlock with corresponding radial lugs 46 on the bowl 41. It is to be noted that the central portion of the bowl 41 and the lining or race 42 are level. The bowl 41 and its lining race 42 are dished upwardly at 47 near the outer periphery thereof. A plurality of balls 48 ride on the dished outer periphery or rim 47 of the bowl lining 42.

From the center of the bowl 41, extends upwardly a hollow column 49 on the top 51 of which is rotatably held the hub 52 of a driving frame 53. The driving frame 53 has thereon lateral diametrically opposite driving arms 54 which interlock with corresponding slots 56 in the top of a driving head 57. A lining or race 58 is provided on the lower face 59 of the driving head 57 so as to engage the balls 48 in such a manner as to hold said balls 48 in the dished outer rim 47 of the bowl lining 42.

The driving head 57 is hollow so that its face 59 extends downwardly outside of the upper column 49. The lower end of the driving head 57 has an annular seat 61 formed on the inside thereof into which fits a coil spring 62. The upper end of the coil spring 62 bears against a complementary seat 63 in the underside of the driving frame 53. The driving frame 53 is also hollow and has spokes 64 connecting the top of its hub 52 to the body thereof from which latter the driving arms 54 project. The hub 52 of the driving frame 53 is shouldered at 67 so as to rest on the top of the column 49. A shaft 68 is journaled in the hollow column 49. The lower end of the shaft has a thrust bearing 69 thereon which is in a recess 71 inside of the column 49 so as to prevent upward movement of the shaft 68. The upper end of the shaft 68 is reduced and is keyed to or otherwise drivingly fits at 72 in the upper portion of the hub 52 of the driving frame 53. A lock nut 73 threaded on the top of the reduced shaft end 72 bears against the top of the driving frame hub 52 so as to hold the frame 53 against upward movement. In this manner the spring 62 urges the driving head 57 and its dished lining 58 unto the balls 48. It is to be noted that the lining 58 has engagement pins 74 thereon which fit into corresponding holes 76 in the underside of the driving head 57 as shown in Figures 3, 4, and 5, so that the lining 58 is compelled to move with the driving head 57. It is to be also noted that the curvature or dish of the lining 58 is such that it provides a race which is not diametrically opposite to the dish of the bowl 41 but is offset so that less than 180° of the ball peripheries are between the respective dished races on the side of the balls facing outwardly from the mill. This holds the balls continuously in the outer dished portion of the bowl leaving the central portion of the bowl unobstructed.

On the top of the driving frame 53 is a hopper 77 which aligns with the spaces between the spokes 64 so as to allow the ore to drop through

said spaces through the hollow driving head 57 past the outside of the column 49 onto the central portion of the bowl 41 and of the bowl lining 42. A cylindrical screen 78 is held in a groove 79 around the outer periphery of the bowl 41. The fineness of this screen 78 determines the degree or fineness of pulverization because the centrifugal force throws the pulverized ore over the rim of the bowl 41 and to the screen 78 and whatever ore is not crushed finely enough to pass through the screen 78 is returned to the bowl 41 for further crushing.

When the milling unit 11 is in place in the machine the stem 34 is rotated by the hub sleeve 22 and thus the bowl 41 and the column 49 are rotated together. The shaft 68, the driving frame 53 and the driving head 57 are rotated in opposite direction to that in which the bowl 41 rotates, by means of a differential transmission mechanism 79. It is to be noted that the lower end of the column 49 is enlarged so as to form a central housing. The bowl 41 has a correspondingly opening 81 in its center. In this housing space is disposed the differential transmission 79. A bevel gear 82 has an exteriorly square hub 83 which fits into a square hole 84 in the top of the stem 34 so that the gear 82 rotates with the stem 34 and with the bowl 41. The bevel gear 82 and its hub 83 are rotatable on a stationary shaft 86. This shaft 86 extends through the center of the stem 34 and has a squared lowered end 87 which fits into a squared hole 88 in the hub 19. In this manner the shaft 86 is held stationary and the stem 34 and the gear 82 rotate around said shaft 86. In the top of the shaft 86 is a square hole 89 into which fits a spider shaft 91. Four arms 92 extend from the top of the spider shaft 91 in a plane at right angles to the axis of rotation of the milling unit 40 and parallel with the face of the gear 82. On the end of the arms 92 are rotatably mounted gears 93 which are in mesh with the bevel gear 82. A driven bevel gear 94 is in mesh with the gears 93 opposite to the bevel gear 82. The upper bevel gear 94 is secured to the drive shaft 68. When the pulverizer unit is rotated the bevel gear 82 rotates with the bowl 41. The bevel gear 82 rotates the vertical gears 93 so as to transmit rotation to the upper bevel gear 94 in 50 a direction opposite to the direction of rotation of the bowl 41. The bevel gear 94 in turn rotates the drive shaft 68, the upper end 72 of which latter in turn rotates the driving frame 53 so as to rotate the driving head 57 and the upper race 58 in a direction opposite to the direction of rotation of the bowl 41.

In operation the milling unit 11 is assembled simply by lowering it onto the standard 28 of the base unit 12 so that the stem 34 rests in the standard 28 and the square end 37 of the stem 34 is engaged with the square bore 38 in the driving hub sleeve 22. At the same time the square end 87 of the stationary shaft 86 is engaged with the square hole 88, in the bottom hub 19. Rotation is imparted to the drive shaft 26 in any usual manner such as by means of an electric motor not shown. The power is transmitted through the gears 24 and 23 to the hub sleeve 22 which latter in turn rotates the stem 34 of the milling unit 11. The bowl 41 and the column 49 rotate with the stem 34. At the same time the transmission 79 rotates the upper driving elements and ultimately the driving head 57 and its lining race 58 oppositely to the rotation 70 of the bowl 41. The ore is fed through the

hopper 77, it falls down along the column 49 to the center of the bowl 41. Clogging of this intake passage along the column 49 is prevented by the agitating effect produced by the rotation of the column 49 in opposite direction to the rotation of the driving frame 53 and driving head 57. Centrifugal force carries the ore outwardly on the surface of the bowl lining 42 and to under the balls 48. The balls 48 are rotated by the tangential forces or turning moments exerted by the bowl lining 42 and the head lining 58 thereon. The dished race of the head lining 58 is closer to the vertical center plane of the balls 48 than the dish at the outer rim of the bowl lining 42. This angular arrangement efficiently rotates the balls around axes of rotation converging upwardly toward the center of rotation of the milling unit 11. This rotation at this angle increases the centrifugal action on the ore without necessitating the increase of the diameter of the bowl 41. In other words the movement of the crushed ore toward the screen 78 is accelerated and a larger volume of ore can be handled without increasing the size of the machine. The rolling of the balls 48 at such convergent angle also reduces frictional resistance and applies greater power to the crushing of the ore. The spring 68 holds the driving head and the head lining 58 yieldably so as to prevent clogging of the machine. Large lumps of ore are quickly dislodged and then ground.

Water is applied in the usual manner and the pulp passing through the screen 78 drops down off the rim of the bowl 41 and inside of the shield cylinder 18 onto the dished housing top 16. The pulp is discharged by gravity through the opening above the lip 17 and onto a usual conveyer or to a machine for performing the next operation on the ore.

The machine operates efficiently. It can be made of comparatively small size yet with comparatively large capacity. For cleaning or repairing it is not necessary to stop the operation entirely because a reserve milling unit 11 can be easily placed in position for continued operation.

I claim:

1. A ball mill comprising a frame, a bowl journaled in the frame, a plurality of grinding balls mounted in the bowl, a column extended upwardly from the center of the bowl, a shaft secured to the upper end of the shaft, said head comprising a hub rigidly secured on the shaft, a plurality of arms formed on the hub and extending downwardly therefrom, a ring connecting the lower ends of the arms, a pair of lugs on the ring, a floating head disposed below the driving head and resting on the balls, said floating head having a central hollow hub with recesses formed in the upper end to receive the lugs on the driving head, and annular flange

at the lower end of the hub and interiorly thereof to form an annular seat, a spring resting on said annular recesses and engaging the ring of the driving head, said ring exerting a yielding 5 downward pressure on the floating head against the balls, and means for driving the bowl and the shaft extending through the column in opposite directions.

2. A ball mill comprising a frame, a bowl journaled in the frame, a plurality of grinding balls mounted in the bowl, a column extending centrally from the bowl, a shaft extending through the column, a driving head secured to the upper end of the shaft, said head comprising a hub 10 rigidly secured on the shaft, a plurality of arms formed on the hub and extending downwardly therefrom, a ring connecting the lower ends of the arms, a pair of lugs on the ring, a floating head disposed below the driving head and resting on the balls, said floating head having a central hollow hub with recesses formed in the upper end to receive the lugs on the driving head, an annular flange at the lower end of the hub and interiorly thereof to form an annular seat, a spring resting on said annular recesses and engaging the ring of the driving head, said ring exerting a yielding downward pressure on the floating head against the balls, means for driving the bowl column and the shaft extending 15 therethrough in opposite directions, and a feed hopper secured to the driving head, said hopper being adapted to deliver ore to be ground between the arms of the driving head and said ore falling by gravity between the arms and through the ring and the hollow hub down into the bowl.

3. A ball mill comprising a frame, a journal support on the frame, a bowl, a shaft of the bowl being journaled in the journal support with freedom of axial insertion and removal, a central 20 hollow column extended from the bowl upwardly; a driving head rotatably journaled on the column, said driving head comprising a hub, a plurality of arms extended downwardly from the hub, a head connecting the lower ends of the arms, a hollow floating head disposed below said driving head and resting on the balls, driving connection between the floating head and the driving head, resilient means to urge the floating head against the balls; a transmission 25 mechanism in the column for transmitting and reversing the rotation of the bowl, a shaft extended from said transmission mechanism through said column and drivingly connected to the hub of the driving head, a driving gear of said transmission being rotated with said bowl, a driving mechanism in said frame, and severable connecting means between the bowl shaft and the driving mechanism.

4. A ball mill comprising a frame, a bowl journaled in the frame, a plurality of grinding balls mounted in the bowl, a column extending centrally from the bowl, a shaft secured to the upper end of the shaft, said head comprising a hub rigidly secured on the shaft, a plurality of arms formed on the hub and extending downwardly therefrom, a ring connecting the lower ends of the arms, a pair of lugs on the ring, a floating head disposed below the driving head and resting on the balls, said floating head having a central hollow hub with recesses formed in the upper end to receive the lugs on the driving head, and annular flange
